UNITED STATES PATENT OFFICE.

EDSON B. CARD, OF WHITE PLAINS, NEW YORK.

DESIGN FOR A DOLL.

59,814.

Specification for Design.

Patented Nov. 29, 1921.

Application filed February 23, 1921. Serial No. 447,331. Term of patent 3½ years.

To all whom it may concern:

Be it known that I, EDSON B. CARD, a citizen of the United States, residing at White Plains, in the county of Westchester and State of New York, have invented a new, original, and ornamental Design for Dolls, of which the following is a specification, reference being had to the accompanying drawing, forming part thereof and showing a face view of a doll illustrating my new design.

I claim;

The ornamental design for a doll, as shown.

EDSON B. CARD.
